UNITED STATES PATENT OFFICE.

JOHN GRASSMANN, OF DAVENPORT, IOWA.

TOOL-GRINDING MACHINE FOR RAILWAY HAND-CARS.

SPECIFICATION forming part of Letters Patent No. 758,833, dated May 3, 1904.

Application filed May 28, 1903. Serial No. 159,132. (No model.)

To all whom it may concern:

Be it known that I, JOHN GRASSMANN, a citizen of the United States, residing at Davenport, in the county of Scott and State of Iowa, 5 have invented a new and useful Tool-Grinding Machine for Railway Hand-Cars, of which the following is a specification.

My invention consists of mechanism attachable to the side edge of the platform or floor 10 of the ordinarily-used railway section or track work hand-car and having a revolving shaft adapted to carry one or another of different sizes of grinding-wheels, the motive power of the car being supplied to said shaft by contact between a friction-pulley thereon resting 15 on top of or against one of the driving-wheels of the car, the drive-wheel end of the car being supported while operating the grinding-wheel to free such driving-wheels from contact with the ground or track, or, if necessary, the device may be used while the car is being operated for locomotion.

The utility of the device consists in the workmen while using the hand-car having 20 in this combination a power grinding-machine convenient at hand for sharpening tools while at work at a distance from shop or other place where heretofore it has been necessary to have such grinding done.

30 In the drawings, Figure 1 is a side elevation of a railway hand-car having my tool-grinding device attached. Fig. 2 is a side elevation of the device detached and on a larger scale than in Fig. 1. Fig. 3 is a top view of the device detached. Fig. 4 is an end view showing that part of the device to the right of branch arm K on Fig. 3. Fig. 5 is a side elevation of the car-supporting truss, showing also a front view of hook N. Fig. 40 6 is a side and front view of wedge-block O. Fig. 7 is a side elevation of the hand-car, the grinding mechanism, and the car-supporting truss in combination, constituting my tool-grinding machine, said truss being lodged on the car end at the left in the drawing. Fig. 45 8, Sheet 1, is a different view without reference-letters of parts of the grinding-machine shown and referred to by letters in Fig. 4 of said sheet.

50 Referring to the drawings, a standard or

upright A, made of iron or other material of suitable strength, is provided of sufficient length to extend vertically across the side edge of the ordinary railway hand-car frame and floor, thence a proper distance above such floor, said upright being fastened rigidly to said frame between the forward and rear wheels of the car by clamp-plate B, as shown in full and dotted lines in Figs. 1 and 2, behind said frame-pieces X X by tightening-bolt C, engaging said upright and clamp-plate, the lower portion of said upright being provided with a row of holes a^2 for said bolt to permit adjustment of said upright at the desired height on the car. 65

Arm D is made of iron or other suitable material and is hung at or near one end with a view to the oscillation up and down of its free end by pivot-shaft E, extending inward from and at right angles with said arm and parallel 70 with the car-axle through bearings or holes a' and a^2 in the upper portion of upright A, said pivot-shaft being fastened rigidly in one of the series or rows of perforations d, preferably square, provided in said arm for convenient adjustment thereof on said upright 75 with reference to the drive-wheel of the car, the outward end of said pivot-shaft E conforming in size and shape to such perforations and being fastened therein by bolt e', 80 screwed into such end with the head of said bolt bearing against the outward face of arm D. Encircling said pivot-shaft and rigid therewith is shoulder or flange e², bearing against arm D when drawn up by bolt e' and 85 also serving as a washer against said upright. Said upright may be forked at its upper portion to provide for the two bearings a' and a^2 , which are desirable for greater stanchness 90 in supporting arm D on its pivot-shaft; but, as shown in the drawings, the upper end of the upright may have a downward bend or hook away from arm D for bearing a^2 . Said pivot-shaft is secured in said bearings by bolt e², 95 screwed into the inside end of said pivot-shaft. Between bearings a' and a^2 said pivot-shaft carries coil-spring F, anchored thereto and coiling about and over said pivot-shaft in the direction of driving-wheel J of the car, the unanchored end of said spring being bent 100

to hook into a depression α^4 on the face of the upright A, whereby said spring will tend to revolve said pivot-shaft and give a downward tendency to the free end of arm D by a force 5 over and above that of gravitation, said arm D by being thus hinged being also adapted to be held up from its operating position in connection with the car-wheel, as by a dog or other suitable means acting between said arm 10 and the vertical plane of its supporting-upright A, without separation of the parts from each other or from the car.

Near its free or "forward" end (so called because in grinding tools the operator will face 15 the driving-wheel of the car, usually the rear wheels) arm D is provided with a fork-arm D', extending outward therefrom, then forward on a horizontal plane, and parallel therewith, said fork-arm D' and arm D carrying, respectively, 20 bearings d^1 and d^2 on a line parallel to the axle of the car, in which bearings revolves shaft G, carrying rigid thereto and between fork-arm D' and arm D friction-pulley H, whose circumferential plane is opposite that of driving-wheel I 25 of the car, so that when the forked end of arm D is brought downward by gravity or the force of coil-spring F said friction-pulley and driving-wheel may come into contact with sufficient force to transmit power from the latter 30 wheel to said shaft G. Said pulley H is made sufficiently large to hold arm D and fork-arm D' off from said driving-wheel, and said shaft G extends both ways beyond the transverse faces of said driving-wheel a sufficient distance 35 to permit securing rigidly on the ends thereof, by any approved means for convenient mounting, an emery or other grinding wheel J and of greater diameter than that of said friction-pulley, only one such grinding- 40 wheel being shown in the drawings.

Fork-arm D' has a branch arm K extending back thereof a short distance and parallel to arm D, in which branch arm K is provided an elongated horizontal slot k , extending horizontally therethrough, in which slot is secured 45 the pivot-arm l of the tool-rest L, extending upwardly at right angles to its pivot-arm, said arm being rigid to said tool-rest, and said slot being adapted to permit setting said rest at 50 any desired point on branch arm K by means of nut l', screwed on the inside end of said pivot-arm l.

For the purpose of holding the end of the hand-car up to free the driving-wheels for independently operating the grinding device, hereinbefore described, I provide a truss, consisting of parts hereinafter described, in connection with a bar especially provided, or, for economy and convenience, with such bar 55 as is commonly in use with such cars—namely, a crow or pinch bar. This bar is given the letter M in the drawings, Sheet 2, and is designed to have rest on the ground and incline longitudinally with the car and over the driving-wheel end thereof, extending through ap-

erture n in hook N, which upwardly engages the driving-wheel end of the car-frame. Said hook N is sufficiently strong to sustain the weight of the car end, as well as the added resistance to its shank in forming said truss, 70 having a wide engaging point and being flat throughout to afford a wide contact-surface against the car, tending to prevent its tipping sideward. The upper part of said hook-shank inclines away from the car and has therein 75 the said aperture n, which is elongated and longitudinal with said hook-shank to permit adjustment of bar M by reason of variation in its incline when resting in said aperture. A wedge-block O is provided, adapted when the 80 car end is raised to free the driving-wheels from the ground to be set up toward the car in the angle of said inclined hook-shank and said bar to bind the latter in said aperture n, said wedge-block having on its upper surface 85 a series of horizontal teeth or cogs adapted to engage corresponding cogs on the under surface of the inclined hook-shank, a groove being provided on the under surface of said wedge-block adapted to receive said bar and tending, further, to prevent swerving side- 90 wise of said bar and car. Guides n' n' are provided on either edge of said hook-shank to hold said wedge-block plumb against it when blocked against said bar. Said block O 95 is hung to said shank on rods n² n², extending horizontally from either side thereof through eyes o o on the corresponding sides of said block and having heads to confine said block thereon. 100

I claim—

1. In a tool-grinding machine adapted to be carried by a railway hand-car and operated by the motive power thereof, an upright detachably fastened to the hand-car frame, an arm pivoted therein and adapted to oscillate up and down, a pivot-shaft rigid on said arm and journaled in said upright, a coil-spring on said pivot-shaft, the grinding-wheel shaft carrying rigid thereon a friction-wheel and journaled in the oscillating end of said arm in position to bring said friction-wheel to rest on the car-driving wheel and be revolved thereby and be accommodated by said oscillating tendency to any unevenness in the car-wheel, or be held entirely away therefrom independently of attachment to the car, pivot-shaft apertures on 110 said arm and bolt-holes in said upright for adjustment of the arm and upright respectively, a truss adapted to hold up the car end, whereby the car-driving wheels are relieved from contact with the ground or track for independent operation of the grinding-machine. 115

2. In a tool-grinding machine adapted to be fastened detachably to the side and end of a 120 railway hand-car and be operated by its motive power, an oscillating arm, a pivot-shaft rigid thereon and journaled in an upright adapted to be clamped rigid on the car, a spring anchored to and coiled around said 125 130

pivot-shaft with its free end bearing against said upright, a friction-wheel rigid on a grinding-wheel shaft journaled in the oscillating end of said arm in position whereby the friction-wheel is adapted to rest against the car-driving wheel and be revolved thereby, said spring being adapted to give downward pressure to the oscillating end of said arm and to assist in maintaining contact between the car-wheel and friction-wheel in grinding on the lateral plane of the grinding-wheel, an upwardly-cleaving hook adapted to engage the car-frame end, an aperture in said hook above the car-floor plane, a bar extending through said aperture and resting on the ground, and means for binding said bar in said aperture at any desired position, whereby the car end is held up to relieve the driving-wheels from contact with the ground or track.

3. The combination, in a tool-grinding machine adapted to be used in connection with a railway hand-car and be operated by the motive power thereof, of an upright detachably fastened to such car, a pivot-shaft in said upright rigid to an arm, adapted to rest in or be held away from position for grinding, said pivot-shaft having a coil-spring anchored thereto, a shaft on said arm carrying grind-

ing-wheels, and a friction-wheel adapted to make contact with the car-driving wheel, a 30 tool-rest, a hook having a broad grasping point and surface upwardly lodged on the car end and having an upwardly-extending shank with its top inclined away from the car, an elongated aperture in said shank, a bar having rest on the ground and inclined longitudinally over said car and through said aperture, a wedge-shaped block in the angle of said bar and hook-shank, having underneath a groove adapted to receive said bar, and on the upper 40 surface thereof horizontal cogs or teeth adapted to engage corresponding cogs on the under surface of said inclined hook-shank, guides for said block projecting downward from the sides of said hook-shank, whereby said block is 45 locked against said bar forming a truss sustaining the car end when lifted to free the driving-wheels from the ground, rods on said hook-shank adapted to slide in eyes on said wedge-block and having heads to confine said 50 block thereon.
